UNITED STATES PATENT OFFICE

JULES BUCHEL, OF NEW ORLEANS, LOUISIANA, ASSIGNOR OF ONE-HALF TO THE
ESTATE OF CHARLES LOUQUE, OF NEW ORLEANS, LOUISIANA

BURNER

Application filed February 17, 1928. Serial No. 254,959.

The present invention relates to burners, such as those known as gas burners, and of a type similar to that known as Bunsen burners.

5 Among the objects of the invention is to provide a novel burner having novel parts, and which will efficiently burn with the desired flame without any danger of extinguishment of the flame upon any variation of gas 10 pressure, whether occurring slowly or suddenly, and without any flashing back of the flame or internal ignition of the combustible mixture, irrespective of the fluctuation in pressure of the gas, or wind blowing the 15 flame, or heating of the burner body, or by reason of the proximity of any flame at any part of the burner, such as the air inlet therefor.

By the present invention, a blue flame is assured at all times under all conditions, except 20 that of completely shutting off of the fuel supply, to which the burner may be subjected. This burner absolutely will not back-fire or flash back. In the usual burner not 25 constructed as that of this invention, any mixture of fuel and air to obtain a blue flame combustion, is always attended by facility in back-firing or flashing back. To reduce this danger, it has been the custom to feed the gas 30 more or less undiluted, but the flame burns with a smoky result due to insufficient dilution and consequent dissociation of the hydrocarbons. When the gas is diluted with air, oxygen, nitrogen or other supporter or 35 non-supporter of combustion, the effect is to decrease dissociation and so promote blue-flame combustion. If air, or oxygen, or the like, be used in excess to produce blue-flame combustion, which is usually the case, the 40 mixture becomes explosive with a high rate of flame propagation and this may, and often does, exceed the efflux velocity of the gas mixture from the orifice of the burner and back-firing is the result. To prevent this the mixture 45 has been made so rich that the coefficient of flame propagation is zero. Such a mixture, however, cannot be burned by an ordinary burner, such as the Bunsen burner, without producing a yellow smoky flame.

50 The present invention, therefore, has

among its objects to wholly eliminate all of these disadvantages by providing a structure such that blue-flame combustion may be effected with a supply of air or oxygen which is so restricted that if the same mixture were fed to an ordinary burner, such as a Bunsen burner, it would produce a yellow smoky flame instead of a clear blue flame. Hence, a specific illustrative embodiment of this invention comprises a two stage expanding passage, such that the gas discharging from the gas orifice or nozzle expands more or less abruptly into the first stage or section of the passage where mixture is effected with air or other supporter of combustion. The air is admitted through a narrow or slot form of inlet passage located at the juncture of the orifice discharge and the first stage passage section. This slot is preferably cut laterally through a side of the passage and transversely of the direction of flow of the gas or mixture, and also to intersect at the juncture mentioned. The floor or lower face of this slot is preferably even with the outlet end of the gas orifice. The mixture then moves at a given velocity to the second stage passage section, which is of greater cross-sectional area than the first stage passage section, to the end that the mixture may more or less abruptly expand and while decreasing its flow velocity, produce eddies that effect a very thorough mixture of the air and gas. The more thorough the mixture before ignition the smaller the amount of excess air or oxygen required to effect blue-flame combustion and this in turn makes for greater stability and resistance to back-firing.

It has been found by experiment with a properly proportioned burner that the reduction of excess air besides conferring non-back-fire properties has the effect of increasing the efficiency of the burner to as much as 8% above that of the ordinary burner, such as the Bunsen. The increased efficiency is largely due to the reduction of excess air and a larger flame volume resulting from the expansion of the gases within the second stage tube, and also to some extent to a lower flame temperature. As the atmosphere contains about 80% of nitrogen, a lower flame

temperature promotes efficiency in that the inert nitrogen of the air absorbs much less heat by being discharged at a lower temperature. Another advantage secured by reducing excess air is that of a perfectly silent action; the more air admitted, the more noisy the burner flame would be.

Heretofore, to secure stable combustion, it was necessary to efflux the mixture at a high velocity which resulted in giving too little time for complete and thorough mixture, an excess of air being accordingly required. In the present invention, the second stage passage section acts somewhat as a damping means, reducing the higher velocity in the first stage to a slower one in the second, such that the kinetic energy is reduced in the ratio of 50 squared to 18 squared. Some of this energy is used to overcome the air resistance at the top end of the burner tube, but the larger portion is dissipated in forming eddies within the second stage section, with the effect of producing a practically perfect mixture before it is exposed to combustion in the air at the outlet of the burner.

This effect is produced at all pressures of the gases, hence fluctuations in pressure do not change the stability of the device. If the gas pressure drops, the air drawn in at the slot is proportionately reduced and vice versa. The damping effect of the second stage section is such that at high velocity of gas flow, the too high induction of air is prevented by reason of increased friction, whereas at low rates the resistance is reduced thus facilitating the induction of air at a time when the kinetic energy of the gas is low and has little propelling force. It also prevents dissipating action on the part of the stream of gas from the nozzle or orifice, which at high rates of flow may pierce the center of the mixture which is rich in the center, and thus passing through it for the length of the burner produces a mixture more or less rich in the center and less so at the circumference. The damping effect will also produce a change in kinetic energy of the system as the gas mixture passes from the smaller to the larger tube. In the larger tube, the mixture loses some of its velocity-energy (kinetic) and acquires pressure-energy (static) to overcome the air resistance at the orifice of the tube without any danger of piercing. When a given burner is turned very low, the kinetic energy of the gas is very small and it has very little propelling power, but, coincident therewith the greatly reduced velocity in the smaller tube likewise reduces the resistance due to eddies and that due to work done at the orifice of the larger or second stage tube. In a properly proportioned burner, the regulating effect is such that it will burn with a blue flame whether turned high or low, and it will have

the same resistance to back-flashing through the range of capacity from 0 to 100%. Moreover, it has never been found possible to ignite the gas at the air orifice when another gas flame is made to impinge against the same; it hisses and splutters but refuses to ignite.

Other objects, capabilities, advantages and features are comprehended by the invention as will later appear and are inherently possessed thereby.

Referring to the drawings, Fig. 1 is a vertical longitudinal sectional view through a burner constructed in accordance with the invention; Fig. 2 is a top plan view of the device; Fig. 3 is a view in side elevation of a fragmentary part of the same; and Fig. 4 is a horizontal sectional view taken in a plane represented by line 4-4 in Fig. 1 of the drawings.

Referring now more in detail to the drawings, the embodiment selected to illustrate the invention is shown connected to a base 1 in the form of a tripod having a pair of short legs 2 and 3 and a long leg 4. The base is hollow to provide a passage 5 to which leads a tube 6 with which may be connected any suitable gas conductor, such as a rubber tube. To the upper end of the passage 5 is threaded a coupling 7 which in turn is threaded to the lower end of the burner tube or body 8. The lower end portion has a passage 9 leading to a gas orifice or nozzle 10, the orifice 10 being of given cross sectional area or diameter when of tubular form. The outlet of the orifice leads into a first stage passage or mixing chamber 11 which is of greater cross sectional area than the orifice 10. The juncture between the orifice 10 and the passage 11 is more or less abrupt having a connecting wall 12 which should be anywhere between 45° and 90°, so that the gas as it issues from the orifice 10, may more or less abruptly expand in the chamber 11.

The chamber 11 in turn leads to a second stage chamber or expanding passage section 13, the juncture between the two being also abrupt and having a connecting surface 14 ranging anywhere between 45° and 90°, so that the gas issuing from the passage 11 into the chamber 13 may more or less abruptly expand, the chamber 13 being of greater cross sectional area than the chamber 11. The second stage passage 13 has an outlet 15 and the upper end of the tube may be provided with a chamfer 16 or similar bevel to aid in the inward flow of the air or supporter of combustion to the flame at the opening 15.

For the purpose of supplying air or other supporter to the gas issuing from the orifice 10, the tube is provided with a laterally cut slot 17 which extends into the lower end of the passage 11 and adjacent to or proximate to the discharge end of the orifice 10, as clear-

ly shown upon the drawings. It is preferable that the bottom surface or floor 18 of this slot be even or level with the discharge end of the orifice 10 as clearly shown. It will 5 also be noted that the inner end of the slot intersects substantially centrally the lower end of the passage 11 just at the discharge end of the orifice 10. The ratios of the cross sectional areas of the first and second stage 10 tubes may be varied in accordance with the fuel used and other conditions. As an example, although not being limited thereto, one of the forms are in the ratio of the area of the second stage tube varying from 2.5 to 15 four times the area of the first stage tube. This may vary upon or in accordance with the smoothness of the inside surface of the tubes. The kinetic energy of the mixture flowing through the first stage is therefore 20 about from 6.25 to sixteen times greater than it is in the second stage tube and the drop in kinetic energy is constant regardless of the rate of combustion. The burner flame cannot crawl down the burner tube because the mixture 25 cannot burn within the tube and its flame propagation velocity is practically zero.

This two-stage burner is stabilized by having the air slot as narrow as possible and cutting it laterally through the side of the 30 tube substantially half way through the burner body as clearly shown upon the drawings. The amount of air admitted to the burner may be determined by the size of this slot and the slot may be varied according to the quality of 35 the gas used. After once determining the exact proportions of these two passages and slots, the device is then fixed and is not adjustable. Any adjustment that might be made is made when first determining the 40 sizes required for these passages. In special cases, the air slot may be made adjustable, if desired.

While I have herein described and upon the drawings shown an illustrative embodiment of the invention, it is to be understood that the latter is not limited thereto but may comprehend other constructions, arrangements of parts, details and features without departing from the spirit thereof.

50 Having thus disclosed the invention, I claim:

1. A burner comprising a series of connected passage sections, each succeeding section being greater in cross-sectional area than 55 that of the preceding section, and a narrow air inlet at the juncture of a pair of said sections.

2. A burner comprising a series of connected passage sections, each succeeding section being greater in cross-sectional area than 60 that of the preceding section, the change of cross-sectional area at said junctures being abrupt, and a narrow air inlet at the juncture of a pair of said sections.

25 3. A burner comprising a series of con-

nected passage sections, each succeeding section being greater in cross-sectional area than that of the preceding section, and a narrow air inlet at the juncture of a pair of said sections, said inlet being in the form of a slot extending transversely through the side of the second section of the series and intersecting the juncture of it and the first section of the series.

4. A burner comprising a gas discharging 75 orifice, an elongated mixing chamber leading from the discharging end of said orifice, an air inlet extending through the side of said chamber and proximate to said discharging end of said orifice, and an elongated expansion chamber leading from the discharge end of said mixing chamber. 80

5. A burner comprising a gas discharging orifice, an elongated mixing chamber leading from the discharging end of said orifice, a 85 narrow air inlet extending through the side of said chamber and proximate to said discharging end of said orifice, and an elongated expansion chamber leading from the discharge end of said mixing chamber, said 90 expansion chamber being of greater cross-sectional area than that of said mixing chamber.

6. A burner comprising a gas discharging orifice, an elongated mixing chamber leading 95 from the discharging end of said orifice, an air inlet extending through the side of said chamber and proximate to said discharging end of said orifice, an elongated expansion chamber leading from the discharge end of said mixing chamber, said expansion chamber being of greater cross-sectional area than that of said mixing chamber, and the cross-sectional area of said mixing chamber being greater than that of said orifice. 100

7. A burner comprising a gas discharging orifice, a first stage chamber of larger cross-sectional area than said orifice and joined at the discharge end of said orifice, a second stage chamber of larger cross-sectional area 110 than that of said first stage chamber and connected to the other end of said first stage chamber, and a narrow air inlet means at the junction of said orifice and said first stage chamber. 115

8. A burner comprising a gas discharging orifice, a first stage chamber of larger cross-sectional area than said orifice and joined at the discharge end of said orifice, a second stage chamber of larger cross-sectional area 120 than that of said first stage chamber and connected to the other end of said first stage chamber and a slot form of air inlet extending laterally into said first stage chamber at the juncture thereof and said orifice. 125

9. A burner comprising a small passage for gas, a larger and elongated passage for receiving the gas from the small passage, and an air admitting slot at the juncture of 130 said small and larger passages, the inner

part of said slot intersecting the larger passage proximate to the outlet end of said small passage.

10. A burner comprising an elongated passage open at one end and having a gas orifice at the other end thereof, and an air admitting slot at the juncture of said orifice and said passage.

11. A burner comprising an elongated passage open at one end and having a gas orifice at the other end thereof, and an air admitting slot at the juncture of said orifice and said passage, said slot being disposed transverse to the length of said passage.

12. A burner comprising an elongated passage open at one end and having a gas orifice at the other end thereof, and an air admitting slot at the juncture of said orifice and said passage, said slot having a floor even with the discharge end of said orifice.

13. A burner comprising an elongated passage open at one end having a gas orifice at the other end thereof, and an air admitting slot at the juncture of said orifice and said passage, said slot extending transversely through a side of said passage.

14. A burner comprising a tubular passage having a series of linear bores of increasing diameter toward the outlet of the passage, and a narrow air admitting means at the juncture of the first and second bores of the series.

15. A burner comprising a tubular passage having a series of linear bores of increasing diameter toward the outlet of the passage, and an air admitting slot arranged at the juncture of the first and second bores of the series.

In witness whereof, I hereunto subscribe
my name to this specification.

JULES BUCHEL.
